DESIGN FOR A COMBINATION CIGARETTE AND VANITY CASE

Ernest L. Warner, Los Angeles, Calif.

Application October 26, 1945, Serial No. 123,229

Term of patent 3½ years

(Cl. D85—2)

To all whom it may concern:

Be it known that I, Ernest L. Warner, a subject of the King of England and a resident of the city of Los Angeles, in the county of Los Angeles and State of California, have invented a new, original, and ornamental Design for a Combination Cigarette and Vanity Case, of which the following is a specification, reference being had to the accompanying drawing, forming part thereof.

In the drawing:

Figure 1 is a perspective view of a combination cigarette and vanity case, showing my new design,

I claim:

The ornamental design for a combination cigarette and vanity case, substantially as shown.

ERNEST L. WARNER.
